UNITED STATES PATENT OFFICE

WILLIAM R. PULKINGHORN, OF LOS ANGELES, CALIFORNIA, ASSIGNOR TO SPRA-O-SAL PRODUCTS, INC., OF LOS ANGELES, CALIFORNIA, A CORPORATION OF CALIFORNIA

WATER-IMPREGNATING DEVICE

Application filed July 25, 1927. Serial No. 208,226.

This invention relates more specifically to a device for chemicalizing flowing water, and is an improvement of my apparatus entitled "Device for impregnating flowing water" for which U. S. Letters Patent No. 1,582,225 is issued to me on April 27, 1926. The apparatus described in the above mentioned patent provided for a single chemical container and a valve for releasing the chemicals therefrom when it was desired to chemicalize the flowing water, and while this form of device proved satisfactory in operation, yet the single chemical charge necessitated a replacement after every use.

By means of my improvement a number of chemical charges may be mounted in the device at a single loading operation, thus enabling a person to chemicalize the water of a bath or shower several times without the necessity of recharging the apparatus. Further as the chemical containers are hermetically sealed all danger of dissolution of the chemicals by fluid leakage prior to an operation of the device is avoided.

It is therefore a chief object of my invention to provide a device that may be readily connected to the fluid discharge pipes of plumbing fixtures, such as showers, bath tubs and the like, and which may be utilized to chemicalize the water flowing through the fixtures in a number of successive operations.

A further object is to provide a device in which the sealed chemical containers carried thereby may be readily opened to release the chemicals into the flowing water when desired.

Other objects and advantages will be apparent from the following specification, reference being had to the accompanying drawings which illustrate an embodiment of the invention, in which:

Fig. 1 is a side elevation of a "built in" bath tub showing the device connected to the shower fixture.

Fig. 2 is a side elevation of the device.

Fig. 3 is an enlarged central vertical section through the device.

Fig. 4 is a transverse section taken on line 4-4 of Fig. 3 looking in the direction indicated by the arrows.

Fig. 5 is a similar section taken on line 5-5 of Fig. 3 looking in the direction indicated by the arrows.

In the embodiment herein shown the device preferably consists of a cylindrical metal casing 5 having at the bottom a transversely disposed fluid inlet opening 6 and a similarly arranged and oppositely disposed fluid outlet 7, the inlet being internally threaded, while the outlet is exteriorly threaded for the reception of a shower spray member 8, or other similar fixture. This casing is designed to hold the chemical containers and the mechanism for puncturing or opening the same one at a time as the device is used. The upper end of the casing is interiorly threaded for the reception of a cover member 9 whose peripheral surface is knurled or serrated for convenient manual rotation, and cast integrally with the cover are downwardly depending cylinders 10, four in number, arranged in circular formation and are provided on their lower ends with cut away portions 11 to enable the insertions and withdrawal of the chemical containers 12 to and from the cylinders when desired. The lower end of cylinders 10 terminate at about the center of the fluid inlet and outlet openings in order that the flowing fluid may contact with the chemical in an opened container during an operation of the device, and also to permit of an unrestricted flow of fluid therethrough.

The chemical containers 12 are formed from relatively stiff paper in cylindrical form, provided with end closures 13 to effectually seal the chemicals disposed therein, the entire surface being preferably treated to a coat of paraffine in order to hermetically seal the same against the action of air or moisture.

Chemical containers 12 are removably supported in the cylinders 10 by means of a rotatable member 14, (best shown in Fig. 5) of flat circular form having segmental openings 15 formed around its circular edge of a slightly greater radius than the radius of the cylinders in order that the member will offer no interference to the insertion and removal of the containers when the openings are brought

into register with the open end of the cylinders. The underface of the cover member is provided with a centrally disposed bearing lug 16, while at the lower ends of the cylinders is a similar bearing lug 17, the bores of both lugs being in alinement. Mounted in the bores of lugs 16, 17 is a shaft 18 that extends beyond the upper surface of the cover member to which is rigidly secured in any suitable manner a hand wheel 19 preferably formed of "bakelite" or other non-corrodible substances.

Mounted on the lower end of shaft 18, is a transversely extending arm 20 secured thereto by a nut 21 carrying on its outer end a double edged shearing knife 22, adapted when the arm is rotated through the medium of the hand wheel 19 to successively form a slotted opening in each of the containers 20 to expose the chemicals carried thereby to the action of the water flowing through the device.

From the above it is thought that the operation of the device will be obvious. In loading the cylinders with filled containers the cover member is unscrewed and upended. The rotatable member 14 is then turned until its segmental openings register with the open ends of the cylinders to permit the insertion 30 of the chemical containers in the cylinders, the member being again rotated over the open ends of the cylinders to support the containers in position. Cover member is then inserted in the casing and secured thereto. When 35 a person desires to obtain a perfumed bath or shower, the hand wheel is rotated to force the shearing knife 22 into engagement with one of the sealed cylinders to form a lateral cut therein to expose the chemical therein to the action of the fluid flowing through the device. The contents of one container will usually be sufficient to perfume or chemicalize a bath or shower of usual duration. Additional baths or showers may be obtained 45 until all the containers are emptied, when fresh ones may be inserted.

As in my patent above referred to the chemicals employed are for the purpose of softening the water, or perfuming the same, and 50 as the salts employed are readily soluble all danger of clogging the device is obviated.

As the chemical containers are formed of inexpensive materials as well as the chemicals employed, it will be apparent that the same 55 may be vended at slight cost.

What I claim is:

1. A device of the class described comprising a casing having fluid inlet and outlet 60 openings, the inlet opening adapted for connection to a source of fluid under pressure, a chemical container formed of a fibrous material mounted in said casing, and rotatable cutter means for forming an opening in said 65 container to release the chemicals contained

therein to impregnate the fluid as it passes through said casing.

2. A device of the class described comprising a casing having fluid inlet and outlet 70 openings, the inlet opening adapted to be connected to a source of fluid under pressure, a hermetically sealed chemical container formed of a fibrous material mounted in said casing, and a rotatable cutter means for forming an opening in said container to release 75 the chemicals contained therein to impregnate the fluid as it passes through said casing.

3. A device of the class described comprising a casing provided with fluid inlet and 80 outlet openings and means to connect the inlet to a fluid pressure supply line, a chemical container formed of a fibrous material detachably mounted in said casing, and rotatable cutter means to mutilate a wall of 85 said container to expose the chemicals disposed therein to the action of the fluid passing through the casing.

4. A device of the class described comprising a casing having fluid inlet and outlet 90 openings the inlet opening adapted to be connected to a source of fluid supply, a sealed paper cylinder for holding a chemical 95 detachably mounted in said casing, and a manually operated shearing knife mounted in said casing for forming an opening in said container to release the chemical therefrom, whereby the water flowing through the casing will be chemicalized.

5. A device of the class described comprising a casing open at its upper end having a fluid inlet and outlet openings adjacent the bottom of said casing, the inlet adapted to be connected to a source of fluid pressure, a closure for the upper end of said casing having 100 a depending cylindrical casing having an open lower end for the reception of a chemical container, means to support the container in said cylindrical casing, a container cutting knife carried by said casing closure and means for rotating the knife to cut the container for releasing the chemicals contained 110 therein to impregnate the fluid as it passes through the casing.

6. A device of the class described comprising a casing having fluid inlet and outlet 115 openings, said inlet opening adapted for connection to a source of fluid supply, the upper end of said casing having a removable closure, a plurality of chambers formed on the 120 underface of said closure for holding chemical containers, said containers being removable, means for supporting the containers in position in said chambers, and rotatable 125 means carried by said closure for forming an opening in the containers successively to release the chemical contained therein to the action of the flowing fluid passing through the casing, whereby to impregnate the fluid.

7. A device of the class described comprising 130

ing a casing open at its upper end and having oppositely disposed fluid inlet and outlet openings adjacent its lower end, said inlet opening adapted to be connected to a source of fluid pressure, a removable closure for said casing having a plurality of compartments open at their lower ends for the reception of chemical containers, a rotatable shaft carried by said closure having means on its upper end to rotate the same, a shearing knife carried by the lower end of said shaft and extending transversely therefrom for successively forming a cut in the wall of each of said chemical containers to expose the chemicals carried thereby to the action of the fluid as it passes through the casing, and a flat circular member having openings in its edge carried by said shaft for supporting the chemical containers in their compartments, said member adapted to be rotated to move the openings therein into register with the open ends of the compartment to permit of the removal of the empty containers and the insertion of filled ones.

25 In testimony whereof I affix my signature.
WILLIAM R. PULKINGHORN.
